UNITED STATES PATENT OFFICE.

JACOB BOUGHER, OF SABETHA, KANSAS.

QUILTING FRAME.

Application filed May 5, 1921. Serial No. 466,900.

To all whom it may concern:

Be it known that I, JACOB BOUGHER, a citizen of the United States, residing at Sabetha, in the county of Nemaha and State 5 of Kansas, have invented certain new and useful Improvements in Quilting Frames, of which the following is a specification.

This invention relates to new and useful improvements in quilting devices and has 10 for its primary object to provide a device to be supported from the ceiling or otherwise suspended from above, whereby it may be readily operated in connection with a sewing machine.

15 A further object of the invention resides in providing a device which is so suspended as to readily respond to the touch of the operator and which may be quickly moved to any desired position.

20 A further object of the invention resides in providing a device which is an improvement in various details over other devices of this character, and which is simple and durable in construction, inexpensive to manufacture and very efficient in use.

25 With these and other objects in view my invention consists in the novel features of construction, combination and arrangement of parts as will be hereinafter referred to 30 and more particularly pointed out in the specification and claims.

In the accompanying drawings forming a part of this application—

Figure 1 is a front elevation of a device 35 constructed in accordance with my invention;

Fig. 2 is a plan view of the frame structure removed from the hangers;

Fig. 3 is an end elevation of the device;

40 Fig. 4 is an enlarged plan view of the frame structure with parts broken away and parts in section;

Fig. 5 is a detail section as seen on the line 5—5 of Fig. 4; and

45 Fig. 6 is a section as seen on the line 6—6 of Fig. 1.

In describing the invention I shall refer to the drawings in which similar reference characters designate corresponding parts 50 throughout the several views, and in which 1 designates a pair of supports suspended from a ceiling or other upper structure 2 and braced by means of the stays 3. These supports secure a wire or cable 4 therebetween, said wire cable being connected with 55

turn buckles 5, which are in turn engaged with an adjustable hook 6 removably secured in the ends of the supports 1, as clearly shown in Fig. 1 of the drawings.

Slidably supported on the wire or cable 60 4 are the trucks 7, each of which consists of a block 8 carrying upstanding brackets 9 between which are carried the grooved rollers 10. A pair of such rollers is provided in connection with each block 8, as 65 clearly shown in Fig. 1 and connected to the end face of each block 8 and diverging therefrom are the guy wires 11. These guy wires extend to and connect with hooks on the upper face of a bar 12 forming the 70 upper part of the quilting frame, by having the guy wires at their lower ends provided with leather straps and buckles designated in the drawings as 13 and fastened to the above mentioned hook on the bar 12 where- 75 by the frames may be adjusted upwardly and downwardly when quilting.

Secured to a face of the bar 12 at its ends, as shown in Fig. 1 of the drawings, are the angular depending hangers 14 80 formed of metal and having the flattened ends 15 formed thereon, to which are adapted to be secured the quilting frame proper.

The quilting frame consists of two end 85 pieces 16 and 17 and countersunk therein intermediate of the ends and projecting outwardly from the same are the threaded bolts 18. These threaded bolts have squared portions 19 formed thereon immediately adjacent the heads thereof, and plates 20 having squared openings therein receiving the squared portions 19 of the bolts therethrough are applied to the outer face of the end pieces 16 and 17, as clearly shown in 90 Fig. 4 of the drawings. The flattened ends 15 of the hangers 14 engage the bolts 18 and pairs of nuts 21 screw the hangers firmly to the end pieces to prevent movement therebetween except when desired. 95 100

Secured between the ends of the end pieces 16 and 17 are the rollers 22 and 23 and an auxiliary roller 24 is held between said end pieces adjacent the roller 23. These rollers are held in place by means of the wood 105 screws 25 and wear plates 26 are secured to the outer faces of the end pieces 16 and 17 through which said screws extend to prevent undue wear on said end pieces 16 and 17, which are preferably formed of wood. The 110

roller 24 is removably applied to the end pieces, the latter being diagonally slotted as shown at 27, and the wear plates 26 in connection therewith being similarly slotted whereby the screws 25 holding said roller 24 in position may be readily inserted or removed through the slotted portions. This structure is clearly shown in Figures 3 and 4 of the drawings.

10 Each of the rollers 22, 23 and 24 is provided with a ratchet 28 at the end thereof adjacent the end piece 17, and pivoted pawls or dogs 29 are carried on the end piece 17 to be engaged with said ratchets when desired. Thus, the rollers may be prevented from being rotated by merely disposing the pawls in connection with the ratchets, as clearly shown in Figs. 4 and 5 of the drawings.

20 In order to permit of the passage of the quilting frame beneath the needle bar of a sewing machine, the end piece 16 is broken adjacent the roller 22 to provide a passage-way or the like 30, and the two sections of the end piece 16 are held together by means of a thin metallic plate 31 which is secured to the lower face of the sections of this end piece, as clearly shown in Fig. 3 of the drawings. This metallic plate being thin permits 30 of the ready passage of the frame under the needle bar, and at the same time prevents strain or tortional movement in the sections of the end piece. Moreover, it supports the sections of the end piece 16 of the device in 35 proper alignment and the roller 22 in parallel relation with the rollers 23 and 24, as clearly shown in Fig. 2 of the drawing.

From the foregoing description of the construction of my improved device the operation thereof will be readily understood, and it will be seen that I have provided a

simple, inexpensive and efficient means for carrying out the objects of the invention.

While I have particularly described the elements best adapted to perform the functions set forth, it is obvious that various changes in form, proportion, and in the minor details of construction may be resorted to without departing from the spirit or sacrificing any of the principles of the invention.

Having thus described my invention, what I claim as new is:

1. In a device of the class described, a supporting cable, a pair of trucks slidably mounted thereon, each of said trucks comprising a base block, upstanding brackets and a pair of grooved pulleys, a pair of guy wires diverging from each of said trucks, a bar connected to the divergent ends of said guy wires, means in connection with said guy wires to permit of relative adjustment of the bar to the supporting cable, hangers removably secured to the ends of said bar, and a quilting frame carried between said hangers.

2. In a device of the class described, a supporting cable, a pair of trucks slidably mounted thereon, each of said truck comprising a base block, upstanding brackets and a pair of grooved pulleys, a pair of guy wires diverging from each of said trucks, a bar, adjusting straps connecting the free lower ends of said guy wires with the said bar to permit the vertical adjustment of the bar with respect to the supporting cable, hangers removably secured and depending from the ends of the said bar, and a quilting frame carried between said hangers.

In testimony whereof I affix my signature. 80

JACOB BOUGHER.
